SCARF

Elsie M. Lewis, Rockville Centre, N. Y., assignor to Edgar C. Hyman Co., Inc., New York, N. Y., a corporation of New York

Application April 27, 1949, Serial No. 2,309

Term of patent 3½ years

(Cl. D3—12)

To all whom it may concern:

Be it known that I, Elsie M. Lewis, a citizen of the United States of America, and a resident of Rockville Centre, in the county of Nassau and State of New York, have invented a new, original, and ornamental Design for Scarf, of which the following is a specification, reference being had to the accompanying drawing, forming a part thereof:

I claim:

The ornamental design for a scarf, substantially as shown.

ELSIE M. LEWIS.
